FIG. 1 is a side elevational view of a trailer embodying my new design, the top being removed;

FIG. 2 is a top plan view thereof;

FIG. 3 is a rear elevational view thereof;

FIG. 4 is a front elevational view thereof;

FIG. 5 is a side elevational view of the trailer of FIG. 1 but with the removable top in place;

FIG. 6 is a top plan view of the trailer and top of FIG. 5;

FIG. 7 is a front elevational view of the trailer and top of FIG. 6;

FIG. 8 is a rear elevational view of the trailer and top of FIG. 6;

FIG. 9 is a bottom plan view of the trailer and top of FIG. 5.

The side opposite that shown in FIGS. 1 and 5 is a mirror image thereof.

I claim:

The ornamental design for a trailer, substantially as shown and described.
